12 Claims. (Cl. 235—61)

1

This invention relates to calculating machines of the partial product type.

Machines of this kind use one set of representations of partial products for each denomination of the multiplicand. Each set, or multiplication table, usually comprises ninety partial products, namely one for each of ten multiplicand digits 0-9 multiplied by each of nine multiplier digits 1-9. This arrangement results in a certain duplication of partial products, since they comprise not only, say, $15=3\times 5$, but also $15=5\times 3$, and so on.

Arrangements are known which comprise only forty-five partial products. In these known arrangements the partial products are so positioned that their selection requires a two-dimensional movement; that is, a partial product is selected by moving the multiplication table in one direction according to the desired multiplicand digit and in another direction according to the desired multiplier digit. Consequently, arrangements of this kind are somewhat bulky and cumbersome.

In order to obviate this difficulty, it has been previously suggested to arrange the partial products in a unilateral manner by spacing them logarithmically, or substantially so. This has the advantage of a reduction in the number of partial products as mentioned above, as well as a further advantage of a simple unilateral movement for the selection of the required partial products. For practical reasons, however, a logarithmic spacing is less convenient than an equidistant spacing. Further, since even the smallest spacing must not be too small for the proper functioning of the machine, and since in such an arrangement the spacings increase rapidly in proportion to the logarithms of digits 1-9, the overall length of such a logarithmically spaced table is considerable. It is desirable, however, to arrange calculating mechanisms in a very compact manner.

The main object of the present invention is to provide, for use in a calculating machine, a multiplication table of simple and compact kind, comprising not more than forty-five representations of partial products arranged unilaterally and equidistantly.

Another object is to provide simple and reliable means for selecting for operation those partial products which correspond to the digits entering into a calculation.

A further object is to provide convenient means for selecting for operation the required partial products by a single unilateral movement of the mechanical multiplication table or tables.

2

Yet another object is to provide means for partial products selection by a single unilateral movement in accordance with the two digits entering into a calculation, irrespective of which digit is the multiplicand digit and which is the multiplier digit.

A further object is to reduce to a minimum the movements required for the selection of partial products.

10 Yet another object is to eliminate partial products whose value is 0.

Other objects will become apparent as the description proceeds.

15 With these objects in view, a multiplication table made according to the present invention comprises physical representations of partial products equidistantly spaced and unidirectionally arranged in groups, the first group comprising the products of the first digit multiplied by all other digits and by itself, the second group comprising the products of the second digit multiplied by all digits except the first, the third group comprising the products of the third digit multiplied by all digits except the first two, and so forth, the last group comprising the product of the last digit multiplied by itself.

20 A mechanism for selective positioning of multiplication tables made according to the present invention comprises an abutment fixedly associated with each group of partial products, means for yieldingly moving the multiplication tables in a single direction, a fixed stop bar extending across the said tables and having a plurality of steps each associated with a digit and equidistantly spaced in the said direction, a pair of locating members associated with each of said tables, either locating member of each pair being adapted on being engaged by one of said abutments to move in the said direction together with the other locating member of the pair until this other locating member engages the said fixed stop bar, means for individually setting the first locating member of each pair according to the desired multiplicand digit, and means for jointly setting the second locating members of all pairs according to the desired multiplier digit.

25 In the accompanying drawings illustrating a preferred embodiment of the present invention:

Figure 1, constituted by Figures 1A and 1B, is a vertical section, substantially on line I—I of Figure 3, showing the multiplicand set-up mechanism.

30 Figure 2, constituted by Figures 2A and 2B, is a vertical section, substantially on line II—II of Figure 3, showing the multiplier set-up mecha-

nism, the carriage being assumed in the extreme left-hand position.

Figure 3 is a horizontal section on line III—III of Figures 1 and 2.

Figure 4 is a partial section on line IV—IV of Figure 1B, and

Figure 5 is a partial section on line V—V of Figure 3.

Partial product plates

In a preferred embodiment of the present invention the partial products are represented by notches of suitable depth cut into pairs of circular discs, one disc of each pair being reserved for the units and the tens, respectively, of the partial products. There is one pair of these discs or plates for each denomination of the multiplicand within the machine capacity.

The units plate 10 and the tens plate 11 are shown in Figures 1A and 2A, respectively. A portion of the periphery of each plate is divided into equidistant spaces occupied by notches arranged in groups, as indicated by numerals 1 to 9 between arrows. Each group of notches is associated with a digit, but this digit is only occasionally associated with either multiplicand or multiplier, as it may be sometimes associated with one factor and sometimes with the other factor. This will be explained as the description proceeds. The notches are arranged according to the following table:

Group	Partial Product	Tens	Units
1	1×9	0	9
1	1×8	0	8
1	1×7	0	7
1	1×6	0	6
1	1×5	0	5
1	1×4	0	4
1	1×3	0	3
1	1×2	0	2
1	1×1	0	1
2	2×9	1	8
2	2×8	1	6
2	2×7	1	4
2	2×6	1	2
2	2×5	1	0
2	2×4	0	8
2	2×3	0	6
2	2×2	0	4
3	3×9	2	7
3	3×8	2	4
3	3×7	2	1
3	3×6	1	8
3	3×5	1	5
3	3×4	1	2
3	3×3	0	9
4	4×9	3	6
4	4×8	3	2
4	4×7	2	8
4	4×6	2	4
4	4×5	2	0
4	4×4	1	6
5	5×9	4	5
5	5×8	4	0
5	5×7	3	5
5	5×6	3	0
5	5×5	2	5
6	6×9	5	4
6	6×8	4	8
6	6×7	4	2
6	6×6	3	6
7	7×9	6	3
7	7×8	5	6
7	7×7	4	9
8	8×9	7	2
8	8×8	6	4
9	9×9	8	1

Thus, the first notch (on the right) of units plate 10 is nine steps deep to represent the units of the product $1 \times 9 = 9$; the corresponding space on the tens plate 11 is not notched, Fig. 2B, since the tens digit of this product is 0, and so on. The last notch (on the left), indicated by the numeral 9, is one step deep on the units plate to represent the units of the product $9 \times 9 = 81$, while the corresponding notch in the

tens plate is eight steps deep to represent the tens of this product.

The first group of partial products contains nine products of the first digit multiplied by all digits; the second group contains eight products of the second digit multiplied by all digits except the first; the third group contains seven products of the third digit multiplied by all digits except the first two, and so on, until the last group which contains only one product of the last digit multiplied by itself. There are altogether forty-five partial products.

Each plate 10, 11 has a cutout with nine abutments 1a to 9a, each of which is associated with the respective group of partial products. Each abutment is so positioned that, when it abuts against locators presently to be described, the first notch of the respective group is aligned with a line S where it may be sensed.

Each pair of plates 10, 11 is fixedly mounted on a bush 12 rotatable on a sleeve 13 slidable on a splined shaft 14 rotatably mounted in the supporting structure of the machine. The two plates of each pair may be rigidly connected by rivets 15; they are properly aligned with each other, so that their notches and abutments 1a—9a correspond exactly. Two locators, namely 16, Fig. 1A, and 17, Fig. 2A, are slidably and rotatably mounted on each bush 12. Each locator 16 has a lug 18 coating with abutments 1a—9a of the units plate 10, while the other locator 17 of each pair has a similar lug 18 coating with abutments 1a—9a of the tens plate 11. A stud 19, Fig. 1B, fixed in the locator 17 engages a slot 20 in the associated locator 16. Thus, locators 16, 17 of each pair are capable of being shifted independently from each other in a horizontal direction by means to be described, and of being rotated jointly due to stud 19.

Sleeve 13 is held between side plates 21, 22 (see also Fig. 3) of a carriage fully described hereafter. A stop bar 23, Figs. 1A, 2A, is fixed to the carriage plates 21, 22; it has nine steps 1s—9s spaced angularly exactly according to the notch spacing of the partial products plates 10, 11.

Locators 16, 17 are identical as far as their lugs 18 and ends 24 are concerned; they are so dimensioned that, when lugs 18 are in the position shown in Fig. 2A in readiness to engage abutments 1a, the ends 24 of the locators are aligned with, and are adapted to engage, the step 1s of the stop bar 23; when a locator is shifted one step to the left as viewed in Figs. 1A, 2A, so that its lug 18 is aligned with abutment 2a, its end 24 is aligned with step 2s, and so on. When both locators of a pair have their lugs 18 aligned with abutments 3a and the plates 10, 11 are rotated clockwise by means to be described, abutments 3a will engage lugs 18 and rotate the locators until their ends 24 abut against step 3s of stop bar 23; the total movement of the associated pair of plates 10, 11 is such that the third ($\times 3$) notch of the third (3) group is brought into the sensing position S. Generally, when the lugs 18 on both locators of a pair are aligned with abutments Na, N being any digit from 1 to 9, the $N \times N$ partial product will be located, upon rotation of plates 10, 11, in the sensing position S.

As will be described in due course, locator 16 of a pair is set according to the multiplicand digit, while the paired locator 17 is set according to the multiplier digit. Assuming the required multiplication is 3×2 , locator 16 will be so shifted that its lug 18 and end 24 are in posi-

tion to engage abutment **3a** and step **3s**, respectively, while lug **18** and end **24** of locator **17** will be in readiness to engage abutment **2a** and step **2s**, respectively. Actually, when the plates **10**, **11** are rotated clockwise, abutment **2a** will engage locator **17** only, since it is nearer to this locator than the abutment **3a** is to locator **16**; continued rotation of plates **10**, **11** will cause locator **17** to rotate around shaft **14**, and due to stud **19** the paired locator **16** will also rotate until its end **24** abuts against step **3s** of stop bar **23**; the rotation now ceases, plates **10**, **11** being so positioned that the notches representing $2 \times 3 = 6$ are in the sensing position **S**.

It is evident that exactly the same result will be achieved if the digits of multiplicand and multiplier are reversed, that is, when the required multiplication is 2×3 . In this case, abutment **2a** will engage locator **16**, while locator **17** will engage step **3s** of stop bar **23**, the product $2 \times 3 = 6$ being again located in the sensing position **S**.

It will be seen that the same product **A** will be located for sensing irrespective of whether its factors are $b \times c$ or $c \times b$. In every case the lug **18** on one of the paired locators is engaged by an abutment **1a**—**9a** associated with the smaller factor, thus selecting the corresponding group of partial products, while the end **24** of the other locator engages a step of bar **23** which is associated with the larger factor, thus selecting the particular product within the group. This arrangement makes it possible to eliminate duplication of partial products and to use only forty-five partial products arranged equidistantly and unilaterally as already described. This also explains why the digit associated with a group of notches in plates **10**, **11** may correspond sometimes to a multiplicand digit, and sometimes to a multiplier digit.

The partial product plates **10**, **11** are releasably or yieldingly rotated by means of driving pawls **25**, Fig. 2A, each of which is pivoted at **26** in the plate **11** and is biased by a spring **27** so that its end protrudes into a cutout or groove of sleeve **13**. When the shaft **14** is rotated clockwise by suitable means (not shown) through part of a full turn, pawls **25** drive the associated plates **10**, **11** until these plates are stopped by their locators **16**, **17** as described, whereupon the suitably sloped ends of pawls **25** are forced out of the grooves in sleeve **13**. After the sensing operation the shaft **14** is restored, whereby the grooves in sleeve **13** pick up the pawls **25** and the associated plates **10**, **11** and restore them to their normal positions shown in Figs. 1A, 2A. In order to prevent rebound, each plate **11** has ratchet teeth coacting with rebound pawls **28**, Fig. 2A, biased by springs **29** and rockable on a shaft **30** fixedly supported in the carriage structure. Prior to the restoring rotation of shaft **14** a crossbar **31** is caused to move upwards, and to disengage the rebound pawls **28** from the ratchet teeth; on completion of the restoring movement bar **31** is restored to its normal position shown in Fig. 2A.

Locators **16**, **17** are restored as the edges of cutouts in plates **10**, **11** engage the lugs **18**; they are guided in slots of a plate **32** secured to the stop bar **23**. When a multiplicand locator **16** is in the 0 position shown in Fig. 1A, its lug **33** is aligned with the edge of plate **32**; thus, when the shaft **14** is rotated, this locator **16** prevents any substantial rotation of the associated pair of plates **10**, **11** irrespective of the position of the 75 74. This multiplicand setting remains visible

associated multiplier locator **17**, so that the unnotched portions of plates **10**, **11** remain in the sensing position **S**.

Multiplicand set-up

Each multiplicand locator **16** has a stud **34**, Fig. 1B, engaging a suitable slot in a slide **35** mounted for horizontal movement in guides **36** secured in the carriage structure. Each slide **35** has a stud **37** engaged by a slot in a rocker **38** rotatable on a shaft **39** fixed in the carriage structure.

Ten keys **40**, Figs. 1A, 3, associated with digits 0 to 9 serve to set up the multiplicand; they are rockable on a shaft **41** fixedly supported in the machine structure. Each key **40**, except that associated with 0, is connected by a relatively strong spring **42** to a rocker **43** mounted adjacent to the associated key on shaft **41**; each rocker **43** coacts with a stud **44** in a striker **45** mounted for horizontal movement on crossbars **46**, **47** secured in the machine structure. Strikers **45** are biased towards the front of the machine by relatively weak springs **48**. As a key **40** is depressed, its rocker **43** causes the associated striker **45** to slide rearwards a predetermined amount, as set by an adjustable stop **49** protruding through a crossbar **50** secured in the machine structure.

Strikers **45** have prongs **51**, **52** adapted to coact with rods **53**, **54**, Fig. 1B, secured in bails **55**, **56** (see also Fig. 3) fixed to a shaft **57** journaled in the machine structure. Bail **55** is extended to form a fork **58** which normally engages an arm **59** of the first (left hand in Fig. 3) rocker **38**. A spring **60** tends to rock the bail structure anticlockwise on to a stop **61**.

When a key is depressed, it causes its striker **45** to slide rearwards, as described, until an abutment **62** of the striker contacts the stop **49**. Meanwhile the upper prong **51** engages the upper rod **53** and turns it until the lower rod **54** abuts against the lower prong **52**. Prongs **51**, **52** are so dimensioned that the rocking movement of the bail structure is exactly representative of the digit associated with the depressed key. This rocking movement is transferred by the fork **58** to the first rocker **38** which causes the associated slide **35** and locator **16** of the first pair of plates **10**, **11** to move accordingly, thus effecting the multiplicand setting. The key continues its downward movement, stretching its spring **42**, until an extension **63** of the key stem, Fig. 1A, trips the carriage shift mechanism 55 presently to be described. The key stroke is limited by a bar **64** secured in the machine structure. When released, the depressed key **40** returns to its normal position on to a bar **65** due to the striker spring **48**.

The 0 key **40** has no rocker **43** and no striker **45**; it serves merely to operate the carriage shift mechanism.

Linked at **66** to each rocker **38**, Fig. 1B, is a connecting rod **67** linked at **68** to a sector **69**, Fig. 1A, rockable on shaft **30**. Sectors **69** are guided in suitable slots in the stop bar **23**; they mesh with gears **70** fast on numeral wheels **71** rotatable on a shaft **72** fixedly supported in the carriage structure. Thus, as a multiplicand locator **16** is set by depression of a key **40**, the associated wheel **71** is rotated accordingly, and the digit associated with the depressed key appears in a window **73** provided in the carriage cover of plates **10**, **11** 74. This multiplicand setting remains visible

after the respective keys are restored and until the multiplicand is cleared as will be described.

Carriage shift mechanism

As shown in Figs. 1, 2, and 3, the carriage structure is formed by side plates 21, 22 interconnected by crossbars 75, 76, 77. Rollers 78 journaled in crossbars 75, 76 run on rails 79, 80 secured in the machine structure. The carriage is biased to the left, as viewed in Fig. 3, by a suitable spring (not shown). An escapement pawl 81, Figs. 1A and 5, is pivoted in the carriage plate 22 and is biased by a spring 82 so that normally its upper tooth 83 is in engagement with a tooth on a rack 84 fixed in the machine structure.

Bails 85, Fig. 1A, are fixed to bar 41 and are interconnected by rods 86, 87. A connecting rod 88 links the lower rod 87 to a rod 89 fixed at each end in a plate 90 rockable on the key shaft 41; a spring 91 anchored in the machine structure normally presses the plates 90 on to the crossbar 65.

Just before a depressed multiplicand key 40 reaches the end of its downward rocking movement, its extension 63 strikes the rod 89 and rocks it slightly rearwards; this causes the bails 85 to rock, too, and the upper rod 86 causes the escapement pawl 81 to rock upwards. As the upper tooth 83 of the pawl disengages the rack 84, the carriage shifts due to its spring approximately half the pitch of rack 94 to the left as viewed in Fig. 5, until a lower tooth 92 on pawl 81 engages the tooth on rack 84. When the depressed key 40 is released, bails 85 are restored by spring 91, and pawl 81 is restored downwards by its spring 82; as the lower tooth 92 disengages the rack 84, the carriage completes its one-step movement, until the upper tooth 83 engages the next tooth on rack 84.

Meanwhile, the fork 58 is restored by its spring 69. In order to ensure that the second half-shift of the carriage does not take place before the fork 58 is completely restored, a delay pawl 93, Figs. 1A, 1B, is rockably mounted on shaft 51. A spring 94 normally presses an arm 95 of the pawl 93 on to the rod 53. When the fork 58 is set clockwise as described, pawl 93 follows until it rests on rod 86. As this rod rocks anti-clockwise to effect the first half-shift, pawl 93 moves up behind the rod 86 and latches it until the fork 58 is restored by spring 60, whereupon rod 53 rocks the pawl 93 out of the way of rod 86, which is then restored by spring 91.

Slides 35 have teeth 96 coacting with an aligner rail 97, Figs. 1B and 4, which has a cutout 98. When the carriage is in the normal position shown in Fig. 3, rail 97 engages a tooth gap in all slides 35 except the first slide (left hand in Fig. 4) which is associated with the first pair of partial products plates 10, 11; thus, all slides 35 are locked in their starting positions 0, except the first slide which is in the setting position, its rocker 38 being engaged by the setting fork 58 as shown in Fig. 3. When now a multiplicand key 40 is depressed, the first slide 35 is set accordingly and the key extension 63 operates the escapement mechanism 86, 81 as described, whereupon the first slide 35 moves to the left out of the cutout 98 and is now positively located in its set position by the rail 97; the second slide 35 is now in the cutout 98, its rocker 38 being in engagement with fork 58 so that it may be set according to the second multi-

plicand digit. This procedure is repeated until the whole multiplicand is set up.

The carriage may be backspaced (moved to the right) by means of a backspacer lever 99 (Figs. 1A, 1B, 3) pivoted at 100 in the machine structure and biased to the left by a spring 101. Pivoted at 102 in the lever 99 is a back-spacer pawl 103 biased on to a fixed stop 104 by a spring 105. Pawl 103 coacts with a rack 106 fixed in the carriage plates 21, 22. When the back-spacer lever 99 is moved to the right in the slot 107 of machine cover 108, pawl 103 comes off its stop 104 and rocks into engagement with the nearest tooth on rack 106; as the lever 99 continues to rock to the right, the rack 106 and consequently the carriage is also caused to move to the right. The movement of lever 99 is limited by stops 109 so as to produce slightly more than one backstep of the carriage, whereupon the carriage is again located by the escapement pawl 81. In order to allow for the back-spacing, pawl 81 and rack 84 are shaped as shown in Fig. 5, pawl teeth 83, 92 and rack teeth being chamfered on opposite sides. Thus, when the carriage is pulled to the left by its spring, the flat flank of tooth 83 positively engages the flat flank of the rack tooth, but when the carriage is backspaced to the right, the chamfered edge of tooth 83 is caused to move up by the chamfered edge of the next rack tooth, whereby the lower tooth 92 rocks up just behind this rack tooth, whereupon the chamfered edge of the second rack tooth causes the chamfered edge of tooth 92 to move down.

As the carriage is backspaced it is necessary to restore the multiplicand slides 35 to their normal positions 0, inasmuch as otherwise their rockers 38 would foul the setting fork 58. To this end each rocker 38 has a shoulder 110, Fig. 1B, coacting with a reset lever 111 pivoted at 112 in the machine structure. A slot 113, Fig. 3, in lever 111 is engaged by a stud 114 fixed in the backspacer lever 99. Normally the parts are in the positions shown; end of reset lever 111 is aligned with that rocker 38 which is in the setting position, but there is sufficient clearance between the edge of reset lever and the shoulder 110 to allow for free setting movement of the rocker. When the carriage is being backspaced, the rocking movement of backspacer lever 99 and stud 114 causes the reset lever 111 to rock clockwise as viewed in Fig. 3, so as to engage the shoulder 110 on that rocker 38 which is about to enter the setting position and to restore the arm 59 of this rocker into alignment with the setting fork 58. Slot 113 is so dimensioned that this restoring movement takes place just after the respective slide 35 has entered the cutout 98 in rail 97, and before the associated rocker arm 59 enters the setting fork 58.

Multiplier set-up

After setting up the multiplicand as described above, the first multiplier digit is set up by depressing a corresponding key 115, Figs. 3, 2A. Multiplier keys 115 are rockable on a shaft 119 fixedly supported in the machine structure; they are biased by springs 117 on to the crossbar 65. A retainer bail 118 pivoted at 119 is biased into engagement with teeth on key plates 120 by a spring 121. Linked at 122 to each key plate 120 is a striker 123 guided on a bar 124; the key stroke is limited by adjustable stops 49 protruding through crossbar 50. Retainer bail 118 serves in a well-known manner to latch the depressed key in the down position; when another key 115 is depressed, it rocks the bail 118 out of the way

and thus unlatches the previously depressed key, which is restored by its spring 117.

Each striker 123 has prongs 125, 126 coacting with rods 127, 128, Fig. 2B, respectively, which are secured in bails 129, 130, Fig. 3, fixed to a shaft 131 journaled in the machine structure; the bail structure is biased by a spring 132 on to a stop 133. When a striker 123 is being shifted by a multiplier key 115, its lower prong 126 contacts the lower rod 128 and causes it to rotate around shaft 131 a predetermined amount associated with the depressed key; at the end of the stroke the upper prong 125 contacts the upper rod 127 and prevents overthrow. Thus, the prongs 125, 126 on strikers 123 are so dimensioned as to produce rotary movements of bails 129, 130 which are representative of the digits associated with the respective keys 115. A rod 134 pivoted in bail 129 is linked at 135 to a bracket 136 fixed to a flat shaft 137 journaled in bearings 138, Fig. 3, 20 in the machine structure. A sleeve 139 slidable on shaft 137 is held between the carriage plates 21, 22; thus, it slides along the shaft 137 according to the positioning of the carriage. Fixedly mounted on sleeve 139 are plates 140, each of 25 which has a pin-and-slot connection 141 to a slide 142 mounted for horizontal movement in guides 36. Each slide 142 has a slot 143 engaged by a stud 144 fixed in a multiplier locator 17. Thus, as a multiplier key 115 is depressed, all 30 multiplier locators 17 are jointly shifted a corresponding amount, in readiness to locate the associated partial products plates 10, 11 as already described.

After a multiplier digit has been set, the partial products are sensed, for instance by racks generally indicated at 145, Fig. 1B, and transferred in any suitable manner to a totalizer 146. This sensing and totalizing mechanism is not a part of the present invention; various mechanisms of this kind are well known in the art. One such mechanism has been described in my prior British patent specification No. 577,330. After the first sensing operation the carriage may be shifted either by hand or automatically, for instance as described in this prior specification, in readiness for multiplication by the next multiplier digit. Depression of the next key 115 cancels the previous setting and resets the multiplier locators 17 according to the next multiplier digit as described, and the process is repeated until the whole multiplication is completed.

Modification

The notches in plates 10, 11 representing the various partial products are not necessarily arranged in the order shown in Figs. 1A, 2A. For instance, they may be arranged in the group order, from right to left: 5, 4, 3, 2, 1, 6, 7, 8, 9, the designations of abutments 1a—5a and of steps 1s—5s in the stop bar 23 being changed accordingly. These groups of notches would represent, respectively, the following partial products:

$$\begin{aligned}
 & 5 \times (9, 8, 7, 6, 1, 2, 3, 4, 5) \\
 & 4 \times (9, 8, 7, 6, 1, 2, 3, 4) \\
 & 3 \times (9, 8, 7, 6, 1, 2, 3) \\
 & 2 \times (9, 8, 7, 6, 1, 2) \\
 & 1 \times (9, 8, 7, 6, 1) \\
 & 6 \times (9, 8, 7, 6) \\
 & 7 \times (9, 8, 7) \\
 & 8 \times (9, 8), \text{ and} \\
 & 9 \times 9.
 \end{aligned}$$

In this modified arrangement the studs 18 on locators 16, 17 when in 1 position will be in the middle of their stroke; they will be moved towards 75

the shaft 14 in order to set up the digits 2, 3, 4, 5, and away from it in order to set up the digits 6, 7, 8, 9, the prongs of key-operated strikers 45 and 123 being shaped accordingly. Thus, this modified arrangement allows of a reduction of the setting movement of locators 16, 17 to four steps in either direction.

Instead of being arranged on rotary discs, the partial products notches or similar representations may be arranged on substantially rectangular plates shiftable in a straight line, the locators being set at right angles to this line.

The invention may be readily adapted to full-keyboard machines and/or to machines wherein the whole multiplier is set up prior to the actual operation. Further modifications, apparent to those skilled in the art, of the partial products plates and associated selective mechanism described above may be made without departing from the spirit of the present invention.

What I claim is:

1. In a calculating machine, at least one set of pairs of stops representing the units and the tens of partial products, the said pairs of stops being equidistantly spaced in a single direction and arranged in groups each associated with a digit of a predetermined sequence of digits and comprising the stops representing the products of the respective digit multiplied by itself and by the following digits, if any, of the sequence, abutments on said set associated respectively with said groups, the spacing of said abutments in the said direction being proportionate to the number of partial product stops in the respective groups, a bar having steps equidistantly spaced in the said direction and equal in number to the number of said groups, a pair of locators selectively settable relatively to the said abutments and to the said bar according to the digits of the multiplicand and the multiplier respectively, and driving means for moving the said set of partial product stops in the said single direction according to the combined setting of the two locators.

2. In a calculating machine, a plurality of sets of paired stops representing the tens and the units of partial products, the said paired stops of each set being equidistantly spaced in a single direction and arranged in groups, each associated with a digit of a predetermined sequence and comprising the stops representing the products of this digit multiplied by itself and by the following digits, if any, of the sequence, abutments on said sets associated respectively with said groups, the spacing of said abutments in the said direction being proportionate to the number of partial product stops in the respective groups, a bar having steps equidistantly spaced in the said direction and equal in number to the number of said groups of partial product stops, a pair of locators operatively associated with each set of partial product stops, multiplicand setting means for individually conditioning one locator of each pair relatively to said abutments and to said bar according to the desired multiplicand digit, multiplier setting means for jointly conditioning the other locators of all pairs in relation to said abutments and said bar according to the desired multiplier digit, and driving means for moving each of said sets in the said single direction and for positioning them individually according to the combined condition of the respective pair of locators.

3. A calculating machine according to claim 2, wherein the said abutments are offset in a second direction at an angle to the said single direction, the steps of the said bar being similarly offset in

this second direction, and wherein the two locators of each pair are individually shiftable by the respective setting means in the said second direction and also are capable of a joint movement in the first-named single direction of spacing of partial product stops.

4. A calculating machine according to claim 2, wherein the said driving means comprise means for moving the said sets of partial product stops yieldingly in the said single direction, and wherein the said bar extends across the said sets in a fixed position.

5. A calculating machine according to claim 2, wherein the said driving means are arranged to move the said sets yieldingly in the said single direction, the said bar fixedly extending across the said sets, and wherein either locator of each pair is adapted on being engaged by one of said abutments to move in the said direction together with the other locator of the pair until this other locator engages the said bar.

6. A calculating machine according to claim 2, wherein one locator of each pair is controlled by the said multiplicand setting means and is operatively associated with a fixed stop adapted to prevent any substantial movement of this locator in the said single direction of spacing of partial product stops, as long as this locator remains conditioned according to the 0 value of the multiplicand.

7. A calculating machine according to claim 2, wherein the said sets of stops representing partial products and the said locators are mounted on a denominational shiftable carriage.

8. A calculating machine according to claim 2, wherein the said sets of stops representing the partial products and the said locators are mounted on a denominational shiftable carriage, and wherein the said multiplicand setting means comprise nine multiplicand keys associated respectively with digits 1 to 9, a common actuator operatively associated with the said keys for conditioning one locator of that pair which is in a predetermined setting position relatively to the said actuator in accordance with the digit associated with an operated multiplicand key, a further key associated with 0, and means operable after each key operation for shifting the said carriage.

9. A calculating machine according to claim 2, wherein the said sets of stops representing the partial products and the said locators are mounted on a denominational shiftable carriage, and wherein the said multiplicand setting means comprise nine multiplicand keys associated respectively with digits 1 to 9, a common actuator operatively associated with said keys for conditioning one locator of that pair which is in a predetermined setting position relatively to the said actuator in accordance with the digit associated with an operated multiplicand key, a further key associated with 0, and means operable after each key operation for shifting the said carriage, further comprising locking means for positively retaining the condition of all locators controllable by the said keys except of the locator which is in the setting position and which is operatively associated with the said actuator.

10. A calculating machine according to claim 2, wherein the said sets of stops representing the

partial products and the said locators are mounted on a denominational shiftable carriage, and wherein the said multiplicand setting means comprise nine multiplicand keys associated respectively with digits 1 to 9, a common actuator operatively associated with said keys for conditioning one locator of that pair which is in a predetermined setting position relatively to the said actuator in accordance with the digit associated with an operated multiplicand key, a further key associated with 0, and means operable after each key operation for shifting the said carriage, further comprising backspacing means for the carriage, and restoring means operatively associated with said backspacing means for restoring the condition of the said locators to that representative of 0.

11. A calculating machine according to claim 2, wherein the said sets of stops representing partial products and the said locators are mounted on a denominational shiftable carriage, and wherein the said multiplier setting means comprise nine multiplier keys associated respectively with digits 1 to 9, and a common actuator operatively associated with the said keys, the said actuator being adapted to condition the second locators of all pairs in accordance with the operated multiplier key, jointly and in any position of the carriage.

12. In a calculating machine, a plurality of pairs of discs notched to represent the units and the tens of partial products, the two discs of each pair being rigidly interconnected and being rotatably mounted on a common shaft, the said notches being equidistantly spaced along the disc circumference in nine groups associated respectively with digits 1 to 9, each group of notches representing the products of the respective digit multiplied by itself and by higher digits if any, nine abutments on each pair of discs spaced at angular distances proportionate to the number of notches in the respective groups and also spaced equidistantly in a radial direction, a fixed bar having nine steps spaced equidistantly both radially and angularly in relation to the said shaft, a pair of locators associated with each pair of said discs, each locator being individually slidable radially to the said shaft into operative association with any one of said abutments and the corresponding step on said fixed bar, each pair of locators being also jointly rotatable around said shaft, and means for yieldingly rotating the said pairs of discs until one locator of each pair is engaged by one of said abutments and the other locator of the pair engages the said fixed bar.

DANIEL BRODIO.
